UNITED STATES PATENT OFFICE.

HOMER PARMELEE, OF BALTIMORE, MARYLAND, ASSIGNOR TO BARTLETT, HAYWARD & CO., OF SAME PLACE.

DESIGN FOR A STEAM-RADIATOR.

SPECIFICATION forming part of Design No. 17,614, dated August 9, 1887.

Application filed July 5, 1887. Serial No. 243,465. Term of patent 7 years.

To all whom it may concern:

Be it known that I, HOMER PARMELEE, a citizen of the United States, residing at Baltimore, in the State of Maryland, have invented a certain new and useful Design for Steam-Radiators, of which the following is a specification.

Figure 1 is a perspective view showing the top, side, and end of the newly-designed radiator; and Fig. 2 is a plan view of the top, these two views being deemed necessary to fully illustrate the design.

The letter A designates the top, and B the base. Each of these parts comprises a plate substantially rectangular in shape, having two parallel sides and two parallel ends. These plates constitute the top and bottom of the radiator. Both of these parts have scalloped edges at the sides and ends. When the radiator is viewed from the top or bottom, these scallops *c* are seen to form the edge contour, and they are the most outwardly-projecting parts, and they extend along the entire sides and ends. The pipes *d* extend vertically between

the top and base, and in the side view it will be seen each pipe is attached to said parts within, and is coincident with one of the scallops. In other words, one of the indentations *c'*, which mark the division between each two scallops, is located between each two pipes. There is presented to the eye the combined effect of scalloped-edge contour at top and base and vertical pipes between the top and base, each pipe occupying or coincident with one of the scallops.

35
I claim—

The design for a radiator herein shown and described, the same consisting of the top and base plate having the scalloped-edge contour, and the vertical pipes between said parts, each pipe occupying or coincident with one of the scallops.

In testimony whereof I affix my signature in the presence of two witnesses.

HOMER PARMELEE.
